[57] CLAIM

The ornamental design for a pull tab for slide fasteners, as shown.

DESCRIPTION

FIG. 1 is a front elevational view of a pull tab for slide fasteners showing my new design;

FIG. 2 is a top plan view;

FIG. 3 is a bottom plan view;

FIG. 4 is a right side elevational view;

FIG. 5 is a rear elevational view.

The broken lines showing numerals are for illustration purposes only and form no part of the claimed design.
